SAMUEL KLOOS, OF ALLIANCE, OHIO.

AUTOMOBILE SIGNAL.

Application filed September 22, 1926. Serial No. 137,128.

It is the object of the present invention to provide a plurality of signals for motor operated vehicles, and which signals are singly and automatically operable by means controlled by the speed of the machine, each signal having a particular significance, to indicate to others, and more particularly the drivers of approaching vehicles, the speed at which the machine so equipped is traveling.

10 The nature and advantages of the invention will be better understood when the following detail description is read in connection with the accompanying drawings, the invention residing in the construction, combination and arrangement of parts as claimed.

In the drawings forming part of this application like numerals of reference indicate similar parts in the several views and wherein:

20 Figure 1 is a view of the operating mechanism, with one part of the casing or housing therefor removed.

Figure 2 is a view partly in section showing how the governor shaft is mounted.

25 Figure 3 is a sectional view on line 3—3 of Figure 2.

Figure 4 is a sectional view on line 4—4 of Figure 2.

30 Figure 5 is a sectional view on line 5—5 of Figure 2.

Figure 6 is a fragmentary sectional view showing how the circuit is completed to one of the signals.

35 Figure 7 is a sectional view on line 7—7 of Figure 6.

Figure 8 is a sectional view on line 8—8 of Figure 7.

In accordance with the present invention, I contemplate the provision of a plurality of signals, each having a particular significance with relation to a predetermined speed of the vehicle, and while these various signals may be mounted on any appropriate part of a vehicle, they are preferably arranged in a 40 lamp casing. One of these lamp casings may be mounted on each of the front and rear fenders of the vehicle and each casing may be divided into three separate compartments. In each of these compartments there is an electric light bulb included in a normally open circuit, while the front of each compartment is closed by a particular color lens. The lens for one compartment is preferably white, for another compartment, yellow and for the 45 remaining compartment red.

As hereinabove stated these signals are selectively and automatically controlled by the speed of the machine, and the mechanism for this purpose is housed within a suitable casing which is preferably made in sections 50 and indicated at 15. This casing is arranged beneath the hood of the vehicle, and has journaled therein a governor shaft 16 which is interposed between the speedometer shaft of the machine, and the speedometer operating shaft which is of the ordinary flexible construction. As clearly illustrated in Figure 2, the governor shaft 16 is received within a coupling sleeve or the like 18 which is suitably threaded for association with the shaft 55 of the speedometer, while the other end of the shaft is slotted as at 19 for association with the flexible speedometer operating shaft above mentioned, which shaft is also coupled or threaded on the extension 20 formed on the adjacent end plate of the casing 15. The coupling sleeve 18 is provided with a threaded element 21 which is received by an annular groove 22 formed in the adjacent end of the shaft 16, which of course allows the latter mentioned shaft to rotate within the sleeve as will be readily understood. Arranged on the under side of the upper end plate 23 of the casing is a disk 24 having a groove for a series of ball bearings 25, which balls also operate in a groove formed in the adjacent end of a collar 26 which is held fixed relatively to the shaft 16 for rotation therewith by means of the threaded elements 27. This collar is formed with a sleeve-like 60 extension 28 which constitutes a stop to limit the movement of the collar 29 longitudinally of the shaft 16, which collar 29 is connected with the collar 26 by the arms 30 which are pivotally connected with these collars and also pivotally connected together as shown in Figure 1. A spring 31 surrounds the sleeve-like portion 28 of the collar 26, and bears against the latter mentioned collar and the collar 29, to normally hold the latter in its 65 normal lowermost position upon the shaft 16. The collar 29 is swivelly mounted upon a sleeve 32 which is mounted to slide upon the shaft 16 together with the collar 29, but which construction permits the collar 29 to rotate with the shaft 16 and with relation to the sleeve 32. Each of the collars 26 and 29 are preferably made in sections so that they can be conveniently associated with the shaft 16, and each collar is slotted or bifurcated as 70

at 33 to pivotally receive the adjacent arms 30 above mentioned which operatively connect the collars as described. The sleeve-like member 32 of the collar 29 is clearly illustrated in Figure 6, and the lower end of this sleeve is formed with arms or extensions 34 which support the spring pressed plungers, constituting the movable contacts of the switches employed in connection with the different signals above mentioned. Each spring pressed plunger is indicated at 35 and the spring for which at 36, each plunger operating in a hollow metallic member 37 which is mounted on an insulated block 38, and held thereon by means of a substantially U-shaped bracket 39, the limbs of which are soldered or otherwise suitably secured to the adjacent sides of the member 37 and the U-shaped member being secured to the insulated block 38 by means of a transverse bolt 40. These spring pressed movable contacts 35 cooperate with fixed contacts so that as the collar 29 forming part of the governor structure, is moved longitudinally on the shaft 16, the said signals are selectively and automatically operated to indicate the approximate speed at which the machine so equipped is moving. Rising from the lower end member 41 of the casing for the mechanism is a hollow boss 42, which boss is slotted at spaced points as at 43 to receive the arms 34, as clearly illustrated in Figure 4, thus guiding the collar 29 and its sleeve-like member 32 in its movements longitudinally of the shaft 16. The movements of these parts against the tension of the spring 31 is limited by the extension 44 on the collar 29 coming in contact with the sleeve-like portion 28 of the collar 26 as illustrated in Figure 2, so that the arms or extensions 34 above mentioned never move entirely out of the slots 43 of the hollow boss 42.

Each of the fixed contacts above mentioned is in the nature of a headed screw or the like indicated at 45 and carried by an insulated plate 46, and which plate is secured to a metallic member 47 in any suitable manner preferably by angle-shaped strips 48 as shown in Figure 7. The head of the fixed contact 45 lies flush with the outer face of the insulated plate 46 as illustrated, while the binding post 49 is screwed into the metallic member 47 and connected with the conducting wire 50. These fixed contacts 45 are stepped vertically, so that as the collar 29 moves upon the shaft 16 in one direction, with the variation of the speed of the machine, one of the movable contacts 35 will be brought into engagement with the adjacent fixed contact 45 of a particular signal, thereby closing the circuit to the signal as will be readily understood. As shown in Figure 5, the current passes from a binding post 51 to the particular movable contact of the switch in use, through a wire 52, and passes through this contact 35 and its cooperating fixed contact 45 through a wire 53 which

leads to the particular signal. Of course the manner in which the signals are wired or connected in the different circuits may vary without departing from the spirit of the invention.

In practice, the spring 31 normally holds the collar 29 and its sleeve-like member 32 spaced its greatest distance away from the collar 26, which of course is the normal position of the parts, these collars forming part of the governor above mentioned. The fixed contacts 45 are of course arranged in the path of movement of the movable contacts 35, so that as the collar 29 is moved along the shaft 16 in the direction of the collar 26, being controlled in its movements in this direction by the speed of the machine, one of the movable contacts will be brought into engagement with its cooperating fixed contact, at a predetermined speed, whereupon one of the signals is called into use. For instance the contacts can be arranged to cause the various signals to be actuated at predetermined speeds of the machine. The white signals will be called into use when the machine is running at a rate of approximately twenty miles an hour, the yellow signals actuated when the machine is traveling at approximately thirty or thirty-five miles an hour, and the red signals operated when the speed of the vehicle reaches approximately forty or forty-five miles an hour. When the speed of the machine reaches twenty miles an hour the circuit to the bulb in the white signal compartment is closed, and when the speed of the machine is increased to approximately thirty or thirty-five miles an hour, the operation of the governor causes the collar 29 to move closer to the collar 26, thereby breaking the circuit to the white signal, and closing the circuit to the yellow signal. Again when the speed of the machine is increased to approximately 40 or 45 miles an hour the circuit to the yellow signal is broken, and as the collar 29 moves closer to the collar 26 of the governor, the circuit to the red signal is automatically closed. Manifestly the invention provides means whereby a plurality of signals, each having a particular significance with relation to the speed of the machine, can be selectively and automatically called into use, thus affording others, and more particularly the drivers of approaching vehicles an opportunity to regulate or control the speed of their machines as the circumstances or conditions may require. The invention is not only simple in construction, and particularly advantageous for the purpose intended, but can be quickly and easily applied to any make of machine without any material alteration therein.

While it is believed that from the foregoing description, the nature and advantages of the invention will be readily apparent, I desire to have it understood, that I do not limit myself to what is herein shown and described and

that such changes may be resorted to when desired as fall within the scope of what is claimed.

What is claimed is:

5 1. In a speed responsive circuit closer, a plurality of fixed contacts, a rotatable shaft, a governor associated with said shaft and including a collar mounted for sliding movement thereon, said collar including a sleeve-like portion, horizontally disposed extensions projecting from the lower end of the sleeve, and a spring pressed laterally movable contact mounted on each extension, and adapted to singly engage the fixed contacts 10 at relatively different speeds of rotation of the shaft.

2. In a speed responsive circuit closer, a plurality of fixed contacts, a rotatable shaft, a governor associated with said shaft and including a collar mounted for sliding movement thereon, horizontally disposed extensions projecting from the lower end of the collar, a block of insulating material mounted on each extension, a casing reposing on

each block and coextensive in length therewith, and laterally movable spring pressed contacts operating within said casing, and adapted to singly engage the fixed contacts at relatively different speeds of rotation of said shaft. 25

3. In a speed responsive circuit closer, a plurality of fixed contacts, a rotatable shaft, a governor associated with the shaft and including a collar mounted for sliding movement thereon, said collar having a sleeve-like portion, horizontally disposed extensions projecting from the lower end of the sleeve, spring pressed movable contacts supported on the respective arms and adjustable laterally to singly engage the fixed contacts at 30 relatively different speeds of rotation of the shaft, and a fixed collar surrounding the shaft beneath said sleeve and having longitudinal slots in which the horizontal extensions move to guide the sleeve longitudinally of 35 the shaft and prevent rotation of the collar. 40

In testimony whereof I affix my signature.

SAMUEL KLOOS.
